COMBINATION ELECTRIC COOKER AND SUPPORT STAND THEREFOR FOR BROILING AND BARBECUING FOOD

Cecil L. McLaren, 257 S. Minneapolis,
Wichita, Kans. 67211

Original design application May 27, 1968, Ser. No. 12,101,
now Patent No. 215,250. Divided and this application
Sept. 15, 1969, Ser. No. 19,787

Term of patent 14 years

Int. Cl. D7—04

U.S. Cl. D81—10

FIG. 1

FIG. 2

FIG. 3

FIG. 1 is a perspective view showing my design;
FIG. 2 is a top view of the design shown in FIG. 1;
FIG. 3 is a side elevational view of the design shown
in FIGS. 1 and 2.

This application is a division of my copending application Ser. No. D. 12,101, filed May 27, 1968, now Pat. No. D. 215,250.

I claim:

The ornamental design for a combination electric cooker and support stand therefor for broiling and barbecuing food, substantially as shown and described.
